UNITED STATES PATENT OFFICE.

WILLIAM C. VAN VLIET, OF BROOKLYN, NEW YORK.

PYCNOMETER SUPPORT AND DAM.

SPECIFICATION forming part of Letters Patent No. 532,120, dated January 8, 1895.

Application filed April 18, 1894. Serial No. 507,963. (No model.)

To all whom it may concern:

Be it known that I, WILLIAM C. VAN VLIET, a citizen of the United States, and a resident of Brooklyn, in the county of Kings and State of New York, have invented a certain new and useful Pycnometer Support and Dam, of which the following is a specification.

My invention consists of an apparatus designed more particularly for use by chemists, physicians, druggists and in laboratories generally to facilitate the holding and filling of pycnometers, specific gravity bottles, &c.

In ascertaining the weight of a given quantity of liquid, at a certain temperature, where great accuracy is sought, as in getting its specific gravity, much difficulty is experienced from liquid adhering to the outside of the pycnometer, and to the necessity, due to this cause, of washing and drying and handling the pycnometer after it is filled, which gives time for evaporation and change in temperature, before the weight can be taken. By my invention these difficulties are largely obviated, for the reason that no overflow is permitted to come in contact with the body of the pycnometer, and only the stopper, and a small part of the neck of the pycnometer, need be washed and dried after filling, which can be speedily done and without taking the body of the pycnometer in the hands.

In the accompanying drawings to which reference is made, Figure 1 is a sectional elevation of my invention showing the pycnometer in place. Fig. 2 is a plan view of the same. Fig. 3 is a detailed view of the upper parts of the supports showing a modified means of adjusting the dam and Fig. 4 is a detailed view showing concaved bars for holding the dam in trough-like shape.

A represents a thin apron of soft india-rubber, or other suitable material, held at two of its edges by rods or bars B, B', and formed with a small aperture a. The said apron is not stretched by the said bars B, B', which bars constitute a frame but is simply held taut, so as not to spread the opening a but permits the material to closely hug the neck of the pycnometer C, when thrust up through it, and thus form the dam a' around the neck of the pycnometer. The frame bars B, B' may be variously supported from any suitable base but I prefer to fit them adjustably

in standards D, D', attached to a table or base E, so that the apron may be raised or lowered to suit pycnometers, or other bottles to be filled, of various heights, and so that the slant of the apron may be varied to facilitate the flow according as to whether the liquid be viscous, or thin, and easy flowing. In the construction shown the bar B is attached to the upper end of the vertical rod F which telescopes into the standard D which latter is provided with a set screw f for holding it at any desired height. The bar B' is journaled at its ends in upright bearing blocks b b attached to a cross-rod B², at the upper end of the vertical rod F' which is telescoped into the standard D'. This latter standard, like standard D, is provided with a set-screw f' for holding the rod F' at any desired position in its vertical adjustment. The rod or roller B' may be turned for drawing the apron A taut, and it is held from backward movement by a pawl and ratchet g as shown in Figs. 1 and 2. Instead of journaling the bar B' to turn on its axis it may be made adjustable horizontally, to and from the bar B, by other means, as by a sliding base B³, held in a head block B⁴ at the top of F' as shown clearly in Figs. 3 and 4, the head block being provided with a set screw h or other means for retaining the proper position to which it may be set.

The pycnometer is placed in proper position for its neck to reach slightly up through the apron or dam A so that it may be filled, stopped, cleaned and dried from above the apron, the dam a' serving to deflect all liquid and cause it to flow down the apron and to support or hold the pycnometer laterally during these operations. In this instance the pycnometer is supported by a rest or stand H which, if desired, may be made vertically adjustable for different sized pycnometers, but this is not necessary, particularly if the apron be made vertically adjustable. The said rest H as here shown is telescoped in the stud H' fixed at the center of the base E and provided with a set screw i for retaining the rest at any desired position.

In some instances the bar B' may be slightly concaved as shown in Fig. 4 to slightly elevate the edges of the apron to prevent liquid from overflowing the sides of the apron; and

the bar B is provided with a trough I to catch the liquid from the apron. This trough is held in place by arms k at the ends of the bar B and may be removed for emptying out 5 its contents.

While I have described my invention as designed for filling and holding pycnometers, I do not limit myself to such use as it may likewise be advantageously used in filling bottles 10 with acids, poisons, liquid colors and for various other purposes.

Having thus described my invention, what I claim as new, and desire to secure by Letters Patent, is—

- 15 1. As a new article of manufacture, a pycnometer support and dam, comprising a frame and supports therefor, and a flexible apertured apron to receive the neck of the pycnometer, attached at its edges to the said 20 frame, substantially as and for the purposes described.
2. In a pycnometer support and dam, the combination of opposite adjustable bars, and

a central rest for the pycnometer, of an apertured apron held by said adjustable bars, 25 above said rest substantially as described.

3. In a pycnometer support and dam an apertured apron, and opposite bars to which said apron is attached, in combination with a central rest for the pycnometer substantially 30 as described.

4. In a pycnometer support and dam the base E and hollow standards D D' attached to the base, in combination with the rods F, F', bars B, B', attached thereto, the apron A 35 attached to said bars and a central rest for the pycnometer, substantially as described.

5. In a pycnometer support and dam the base E and hollow standards D D' and H' and the vertically adjustable rods F F' and rest 40 H in combination with the bar B, apron A and adjustable bar B', substantially as described.

WM. C. VAN VLIET.
